UNITED STATES PATENT OFFICE.

KARL SCHLIEPMANN, OF ST. CHARLES, MISSOURI, ASSIGNOR TO ST. LOUIS CAR COMPANY, OF ST. LOUIS, MISSOURI, A CORPORATION.

SASH-BALANCE FOR CAR-WINDOWS.

SPECIFICATION forming part of Letters Patent No. 790,321, dated May 23, 1905.

Application filed January 3, 1905. Serial No. 239,523.

To all whom it may concern:

Be it known that I, KARL SCHLIEPMANN, a citizen of the United States, residing in St. Charles, in the county of St. Charles and State 5 of Missouri, have invented certain new and useful Improvements in Sash-Balances for Street-Car Windows, of which the following is a full, clear, and exact description, reference being had to the accompanying drawings, 10 forming part of this specification.

My invention relates to a sash-balance for street-cars, the object of the invention being to so mount the balance-drum that it may partake of a swiveling motion to avoid kinking 15 of the metal balance-ribbon in lowering and raising the sash connected thereto, which being set at an angle to a perpendicular line is necessarily first raised at an angle to unseat it from the sash-rail before lowering it into the 20 pocket between the inner and outer panels of the car.

Figure I is a vertical section taken through a portion of the side wall of a street-car, including a sash and my balance connected thereto. Fig. II is an elevation of the parts shown in Fig. I with portions in vertical section. Fig. III is an enlarged vertical section taken on line III-III, Fig. I. Fig. IV is an enlarged horizontal section taken on line 30 IV-IV, Fig. III. Fig. V is an edge view of the drum and hanger of my sash-balance.

A designates the inner panel, and B the outer panel, of a street-car side wall. Between these panels is a sash-receiving pocket C, that 35 is closed by a trap-door D.

E is a panel-rail surmounting the outer panel.

F is one of the window-posts containing the sash-runway G, that extends upwardly from 40 the sash-pocket C. This sash-runway is wider at its lower end than at its upper end to permit of the sash H being swung outwardly to rest upon the sash-rail E or move inwardly to be lowered into the sash-pocket when the 45 trap-door D is open.

1 designates one of a pair of sash-balance ribbons secured at 2, Fig. II, to the sash H.

3 is a drum to which the balance-ribbon 1 is secured and on which it is wound. Passing 50 transversely through the drum 3 is a

spindle 4, that is surrounded by a convolute spring 5, one end of which is fixed to said spindle and to the other end of which is fixed said drum at its interior.

The sash-balance parts as thus far described 55 are of common form, and no invention *per se* is herein claimed for such parts.

6 designates a hanger-yoke in the arms of which the spindle 4 of the balance-drum is fitted, said hanger-yoke being provided at its 60 upper ends with pintles 7.

8 represents brackets secured to a fixed portion I of the car-body and apertured to receive the pintles of the hanger-yoke 6, thereby providing for the swinging of the hanger- 65 yoke to permit sway of the sash-balance drum.

It will be seen that by mounting the sash- balance drum and its hanger so that they may swing the said drum is rendered susceptible of moving into direct alinement with the sash 70 8, to which the balance-ribbon is connected, irrespective of the positioning of the sash in a vertical line or out of a vertical line. Therefore when the sash is swung outwardly in its uplifted position and resting upon the sash- rail the balance-ribbon will extend in a straight line from the sash to the balance-drum, and when the sash is raised and moved into perpendicular position to be lowered into the receiving-pocket C the balance-drum will 80 follow the movement, thereby avoiding the occurrence of kinking of the balance-ribbon.

I claim as my invention—

1. In a sash-balance for street-cars, the combination of a balance-drum, a balance-ribbon 85 connected to said drum, a hanger in which said drum is rotatably mounted, and brackets in which said hanger is swingingly mounted, substantially as set forth.

2. In a sash-balance for street-cars, the combination of a balance-drum, a balance-ribbon connected to said drum, a hanger in which said drum is rotatably mounted, pintles extending from said hanger at its upper ends, and supporting-brackets in which said pintles 95 are loosely fitted, substantially as set forth.

KARL SCHLIEPMANN.

In presence of—

H. F. NOGEL,
M. H. MURPHY.
